UNITED STATES PATENT OFFICE.

WILLIAM P. CLARK, OF ELBERTON, GEORGIA.

CAR-COUPLING.

SPECIFICATION forming part of Letters Patent No. 431,333, dated July 1, 1890.

Application filed January 3, 1890. Serial No. 335,743. (No model.)

To all whom it may concern:

Be it known that I, WILLIAM P. CLARK, of Elberton, in the county of Elbert and State of Georgia, have invented a new and Improved Car-Coupling, of which the following is a full, clear, and exact description.

My invention relates to an improvement in automatic car-couplings in which a latching draw-bar is employed, the object being to provide a simple practical device, whereby a secure coupling may be effected between adjacent cars without danger to the operator.

To this end my invention consists in certain features of construction and combinations of parts, as hereinafter described, and indicated in the claims.

Reference is to be had to the accompanying drawings, forming a part of this specification, in which similar letters of reference indicate corresponding parts in all the figures.

Figure 1 is a front elevation of a car with the coupling thereon. Fig. 2 is a side elevation of the coupling, broken away and in section, the device being attached to adjacent cars, and one in coupled condition; and Fig. 3 is a detached sectional view of the coupling, showing the working parts in positions relatively assumed when the draw-bar is being disconnected from the draw-head.

30 A represents the drawhead, preferably cast from metal and provided with an interior recess of proper shape to receive the working parts. The recess has parallel side walls, and its front portion or throat is substantially 35 rectangular in cross-section, as shown in Fig. 1, the outer corner of the lower wall of the draw-head body being cut away and rounded to facilitate the introduction of the draw-bar B. A projecting radial flange a is formed on 40 the front of the draw-head A to increase its area at the front, the inner corners of the side and top walls being rounded also to direct the draw-bar into the throat-cavity. At 45 b in the draw-head a portion of its lower wall is cut away, producing a vertical shoulder at b', whereon the hook end of the draw-bar B may latch, said draw-bar having latch-hooks c formed on each end, which depend from the lower side thereof when in use.

50 A rocking dog D, provided with two limbs d d', is pivoted in the recess of the draw-head A. Said limbs are divergent in bell-

crank form, the limb d being tapered toward its free end that projects toward and near to the vertical shoulder b', so that this end of 55 the rocking-dog limb d will lie below the latch-hook of the draw-bar B when the same is in coupled adjustment with the draw-head body. The limb d' of the rocking dog assumes a nearly vertical position when the other limb 60 is prostrate and below the hook c of the draw-bar B, and is engaged by the pendent pivoted locking-block e, that is forwardly pressed by the spring e', which may be a spiral or plate spring, the latter named being preferred 65 and shown in position. The rocking support of the dog D is extended beyond the wall of the draw-head A as a shaft f, which is supported revolvably near its outer end by the depending bracket-arm g, that is 70 secured to the car-frame near the side of the car. A handle h, affixed to the end of the shaft f, affords means to rock the dog D, when necessary.

In operation the draw-bar B is thrust within 75 the draw-head A, and from the obvious action of the working parts is held therein, the shoulder at e' on the block e preventing the bar from falling or inclining downwardly from a horizontal position at its outer end. 80 The couplings on the cars being alike in construction, the opposite end of the draw-bar, which projects forwardly, will enter the throat of an opposed draw-head on an approaching car, when the nose of the hook c will engage 85 the shoulder e' of the block e and rock it rearwardly, thereby permitting the hook end c to drop and engage the shoulder b', when the resilience of the spring e' will project the pendent locking-block e forwardly, arranging 90 the parts as shown in Fig. 2, which will effect a secure automatic coupling of the two cars. By manipulation of the handle h the rocking dog D may be caused to partially revolve, so as to lift its limb d, thus disconnecting 95 the latch-hook c by the simultaneous rearward movement of the other limb d', whereby the release of the draw-bar is accomplished with safety to the operator.

Having thus fully described my invention, I claim as new and desire to secure by Letters Patent—

1. In a car-coupling, the combination, with a draw-head, of a rocking dog in bell-crank

form, a pendent spring - actuated locking-block, and a draw-bar provided with a latch-hook at each end, substantially as set forth.

2. In a car-coupling, the combination, with 5 a draw-head having a recess therein, a vertical locking-shoulder formed in said recess, a rocking dog of bell-crank form pivoted on a transverse shaft in said recess, and a spring-actuated pendent locking-block in said recess, of a draw-bar having latch-hooks, which project from the same side on each end, substantially as set forth.

3. In a car-coupling, the combination, with a draw-head having an internal recess formed 15 with a rounded front edge on its throat-wall, and a vertical locking-shoulder on the bottom wall of the draw-head in said recess, of a bell-crank-shaped rocking dog, a pendent locking-block having a locking-shoulder near

its pivot-point, a spring normally pressing on 20 the locking-block to throw it forward, and a draw-bar having a depending latch-hook on each end, substantially as set forth.

4. In a car-coupling, the combination, with a draw-head having an internal recess and a 25 locking-shoulder formed in said recess, and a draw-bar provided with a depending hook on each end, of a rocking dog of bell-crank form, a pendent locking-block having a shoulder adapted to engage one limb of the rocking 30 dog, a spring bearing on the pendent locking-block, a transverse shaft forming the pivot of the rocking dog, and means for rotating said shaft, substantially as set forth.

WILLIAM P. CLARK.
